HEEL PLATE

Leon Weinstein, St. Louis, Mo.

Application July 8, 1932, Serial No. 621,346

4 Claims. (Cl. 36—74)

This invention relates to a certain new and useful improvement in heel-plates and has for its object the provision of a heel-plate that may be cheaply and economically manufactured, that 5 may be readily attached to the shoe-heel, and which as a wear-plate is durable and efficient.

And with the above and other objects in view, my invention resides in the novel features of form, construction, arrangement, and combination of parts presently described and pointed out 10 in the claims.

In the accompanying drawing,—

Figure 1 is a plan view of the die-cut blank for the formation of the heel-plate of my invention;

Figures 3 and 4 are, respectively, transverse and longitudinally sectional views of the plate 20 taken approximately along the lines 3—3 and 4—4, Figure 2;

Figure 5 is a reduced elevational view of the plate in operative attached location on a shoe-heel;

25 Figure 6 is a plan view of the die-cut-blank for the formation of a slightly modified heel-plate embodying my invention;

Figure 7 is an inverted plan view of the modified plate constructed from the blank of Figure 30 6; and

Figure 8 is a reduced plan view of the modified plate of Figure 7 in operative attached position on a shoe-heel.

Referring now more in detail and by reference 35 characters to the drawing, which illustrates practical embodiments of my invention, the finished plate A, Figure 2, is constructed of a die or otherwise cut, stamped, or formed sheet-metal blank, Figure 1, which includes a body-portion a of general segmental contour having integral extensions b, c—c, and d of the form or shape 40 shown upon its four margins. By means then of suitable forming dies, either compound with or separate from the cutting or stamping die, said 45 several extensions are bent laterally to rearwardly project approximately at right-angles to the under face of the body a and respectively provide upon the body a;

50 A rear or outer flange 1 extending from side to side of body a along the body outer margin, of greatest height in the so-called longitudinal center of body a and then tapering in height toward the opposite ends or sides of body a, and 55 preferably equipped with a sharp edge;

Suitably pointed outer corner prongs 2 and side flanges 3; and

Suitably pointed inner corner prongs 4 and an inner flange 5.

As shown, the side flanges 3 are each preferably 60 provided with a sharp edge, are presented rearwardly along the body-side margins, and taper in height from the outer prongs 2 towards the inner prongs 4, while the preferably also sharp-edged inner flange 5 is presented rearwardly along the body inner margin. Further, as shown, the outer prongs 2 align or register with the respective side flanges 3 and the inner prongs 4 align or register with the inner flange 5. Thus the inner prongs 4 are angularly disposed with 65 respect to the outer prongs 2, and the opposed prongs 2 and 4 consequently efficiently function in securing the plate A to and upon a shell heel without the employment of any additional securing or fastening devices.

70 Within its area, the plate-body a is also formed with a series of suitably spaced radially disposed body-re-enforcing depressions 6 pressed rearwardly, as shown, from the outer face of the body and of greatest width and depth adjacent the 75 body outer margin, the several respective depressions 6 tapering in width and depth towards the body inner margin, where said depressions are each approximately pointed and of little or exceedingly shallow depth.

75 As so constructed, the plate A may be readily attached to a heel H without the employment of any additional fastening elements, the prongs 2 and 4 and flanges 3 and 5 functioning not only to securely retain the plate upon the heel, but 80 to also prevent the entrance intermediate the plate and heel of any foreign particles that might work to loosen the plate.

85 Further, the depressions 6 give the plate a roughened work surface, preventing slipping and 85 adding to the wearing properties of the plate.

The modified heel-plate A' of Figures 6, 7, and 8 follows generally the structural form and 90 contour of plate A, except that the flange 5 is omitted and replaced by a tongue 7 extending 100 inwardly in approximately the plane of the body a' and provided centrally with an aperture, as at 8, whereby the plate A' may be first pivotally attached to the heel or lift H' and then swung to the desired location, the attachment of the plate 105 A' to the heel lift H' being re-enforced by additional fastening members, if desired, for which purpose the plate A' adjacent its outer margin has suitably spaced accommodating openings 9 adapted first for registration with some of the 110

nail-openings with which standard rubber-heel-lifts, such as the lift A', are usually provided. As so constructed, this form of the plate is especially adapted for use with rubber-heel-lifts 5 and temporarily attached may be supplied the dealer directly with the lift, the plate being subsequently fixed to the heel-lift by the user at the location desired.

In either form, the plate fulfills in every respect the object stated, and it is to be understood that changes in the form, construction, arrangement, and combination of the several parts of the plate may be made and substituted for those herein shown and described without departing 10 from the nature and principle of my invention.

Having thus described my invention, what I claim and desire to secure by Letters Patent is,—

1. A shoe-heel plate integrally including an approximately segmental metallic body having inwardly converging side margins, an arcuate outer margin connecting the outer ends of the side margins, and an inner margin chordwise connecting the inner ends of the side margins, heel-attaching lateral prongs presented rearwardly from the body at the outer ends of its side margins, other heel-attaching lateral prongs presented rearwardly from the body at the outer corners of its inner margin, lateral flanges presented rearwardly from the body and extending along its side margins from said outer prongs to its inner margin, a second lateral flange presented rearwardly from the body and extending along the inner margin from one inner prong to the other inner prong, and a third lateral flange presented rearwardly from the body and extending along its outer margin from one outer prong to the other outer prong, said prongs each having a length greater than the height of said flanges, said side flanges being of greatest height adjacent the outer prongs and tapering in height toward the body inner margin.

2. In a heel plate, an approximately segmental metallic body having inwardly converging side

45

margins, an arcuate outer margin connecting the outer ends of the side margins, and an inner margin chordwise connecting the inner ends of the side margins, the body being integrally formed along its margins with lateral rearwardly presented flanges and within the confines of said flanges with a series of spaced radial depressions pressed rearwardly from the body outer face, said depressions being of greatest depth adjacent the body outer margin and tapering in depth toward the body inner margin.

3. In a heel plate, an approximately segmental metallic body having inwardly converging side margins, an arcuate outer margin connecting the outer ends of the side margins, and an inner margin chordwise connecting the inner ends of the side margins, the body being integrally formed along its margins with lateral rearwardly presented flanges and within the confines of said flanges with a series of spaced radial depressions pressed rearwardly from the body outer face, said depressions being of greatest width and depth adjacent the body outer margin and tapering in width and depth toward the body inner margin.

4. In a heel plate, an approximately segmental metallic body having inwardly converging side margins, an arcuate outer margin connecting the outer ends of the side margins, and an inner margin chordwise connecting the inner ends of the side margins, the body being integrally formed along its margins with lateral rearwardly presented flanges and within the confines of said flanges with a series of spaced radial depressions pressed rearwardly from the body outer face, said depressions being of greatest width and depth adjacent the body outer margin and tapering in width and depth toward the body inner margin, and the side margin flanges also tapering in depth toward the body inner margin and adjacent the body outer margin having a depth greater than the depth of said depressions.
